plate is formed as a portion of a cylindrical surface whose axis of curvature is also on the axis of the top roll. In the modified construction shown in Fig. 6, the top surface of the turnplate is curved as in Fig. 4 while the V-shaped grooves 8a are of gradually decreasing depth from the cane roll towards the bagasse roll. To create such structure the bottoms of the grooves are formed on arcs whose centers lie in a line parallel to the axis of the top roll 2 and a short distance to the left thereof as the rolls are viewed in Fig. 1.

The turnplate described is used in connection with a top roll having a longitudinal grooving 9 cut across the V-shaped girth grooving 16 and 15 providing teeth 10 which engage with the cane. Such engagement insures the movement of the cane across the turnplate at the peripheral speed of the top roll 2 and insures the feeding of the cane to the top and bagasse rolls without any tendency for the cane to pack between the top roll and turnplate. The turnplate being grooved in alignment with the cane and bagasse rolls, the cane as it passes across the turnplate is held in the shape given it as it passes between the cane and top rolls and there is no possibility of the cane being redistributed so that the cane is shaped to fill the grooves of the bagasse roll as well as those of the top roll thus causing the juice extracted by the top and bagasse rolls to be directed back towards the turnplate and not carried off in the bagasse.

The turnplate, having the same axis of curvature as the top roll, can be set close to the top roll while the longitudinal grooving of the top roll, by causing the continuous movement of the cane, insures a much lower pressure than is usually established between the top roll and the turnplate thus increasing the effective pressure applied to the cane between the top roll and the cane and bagasse rolls. Where the depth of the turnplate grooves is gradually lessened, as in the construction shown in Fig. 6, a slightly increased pressure is applied to the cane at the discharge edge of the turnplate due to the decreased cross-sectional area, thus preventing any absorption of the juice at this point and helping to insure the continuous movement of the cane.

Modifications within the scope of my invention will occur to those skilled in the art. Therefore, I do not limit it to the exact form of the parts as illustrated and described.

What is claimed is:

1. In a cane mill having grooved top and cane rolls, said cane roll having parallel V-shaped girth grooving, a turnplate having an upper surface coaxial with said top roll, parallel V-shaped grooves in said upper surface aligned with each of similar grooves of said cane roll and having the groove bottoms lying in arcs coaxially with the axis of said top roll.

2. In a cane mill having grooved top and cane rolls, said cane roll having parallel V-shaped girth grooving, a turnplate having an upper sur-

face coaxial with said top roll, parallel V-shaped grooves in said upper surface aligned with each of said grooves of said cane roll and progressively diminishing in depth toward the discharge edge of said plate, the bottoms of said grooves lying in arcs having their centers in a line parallel to but offset from the axis of said top roll.

3. In a cane mill having grooved top and cane rolls, said cane roll having parallel V-shaped girth grooving, a turnplate having an upper surface coaxial with said top roll, V-shaped parallel grooves in said upper surface aligned with each of said grooves of said cane roll and progressively diminishing in depth towards the discharge edge of said plate.

4. In a cane mill, a cane roll having girth grooving, a top roll having girth and longitudinal groovings forming teeth, and a turnplate with a concave arcuate surface having parallel grooves extending across the surface over which the cane moves, and each of said grooves in the turnplate aligned individually with each of similar grooves of said cane roll and cooperating with said teeth on said top roll in the movement of cane across said turnplate.

5. In a cane mill having grooved cane and top rolls, said cane roll having parallel V-shaped girth grooving, a turnplate having V-shaped parallel grooves aligned with each of said grooves of said cane roll, said turnplate having its upper surface coaxial with said top roll, said grooves in cooperation with the top roll forming a passage of less cross-sectional area at the rear edge of said plate than at the forward edge.

6. In a cane mill having a top roll, a cane roll having V-shaped girth grooving, a turnplate having a concave surface cooperating with the surface of the top roll between which surfaces the cane moves under pressure, said turnplate having parallel V-shaped grooves across said concave surface from the feeding edge to the discharge edge aligned individually with each of said grooves of the cane roll and preventing redistribution of material acted upon by said rolls.
